D 5399

UNITED STATES PATENT OFFICE.

JAMES L. JACKSON, OF NEW YORK, N. Y.

DESIGN FOR HOOKS FOR HARNESS.

Specification forming part of Design No. 5,399, dated December 5, 1871.

To all whom it may concern:

Be it known that I, JAMES L. JACKSON, of the city and State of New York, have invented or produced a new and original Design for Hooks for Harness, &c.; and the following is declared to be a correct description of the same.

This design relates to the shape and configuration of the hook.

In the drawing the said hook is shown by a perspective view.

The hook or arm *a*, back plate *c*, and side plates or brackets *b* are cast together. The hook *a* is hollow and semicircular, and the sides are ex-

tended downward near the back plate *c* in the form of brackets at *b*, which not only strengthen the harness-hook, but render the same highly ornamental.

I claim as my invention—

The design of the shape and configuration of the hook *a* with the bracket portions *b*, as represented.

Signed by me this 13th day of July, A. D. 1871.
JAMES L. JACKSON.

Witnesses:

HAROLD SERRELL,
GEO. T. PINCKNEY.
